US00D531607S

(12) **United States Design Patent** (10) **Patent No.:** **US D531,607 S**
Kim et al. (45) **Date of Patent:** **** Nov. 7, 2006**

(54) **PORTABLE PHONE**

(75) Inventors: **Young-Sae Kim**, Palo Alto, CA (US);
Chi-Young Ahn, Seodaemun-Gu (KR);
Beom-Ku Han, Seoul (KR);
Chang-Hwan Hwang, Goyang-Si (KR)

(73) Assignee: **Samsung Electronics Co., Ltd.**,
Suwon-si (KR)

(**) Term: **14 Years**

(21) Appl. No.: **29/234,727**

(22) Filed: **Jul. 22, 2005**

(30) **Foreign Application Priority Data**

Jan. 26, 2005 (KR) 30-2005-0002651

(51) **LOC (8) Cl.** **14-03**

(52) **U.S. Cl.** **D14/138**

(58) **Field of Classification Search** D14/137,
D14/138, 147-148, 247-248, 144, 496, 156,
D14/341-347; 379/433.01-433.13; 348/14.02,
348/14.01, 376; 455/575.4, 566, 575.1, 556.1,
455/556.2, 90.3; D21/329, 331, 333; D16/208
